UNITED STATES PATENT OFFICE.

JOHN P. BEARDSLEE, OF TAMA, IOWA, ASSIGNOR OF ONE-HALF TO J. M. WRIGHT, OF TAMA, IOWA.

VENDING-MACHINE.

SPECIFICATION forming part of Letters Patent No. 752,322, dated February 16, 1904.

Application filed September 22, 1903. Serial No. 174,224. (No model.)

To all whom it may concern:

Be it known that I, JOHN P. BEARDSLEE, a citizen of the United States, residing at Tama, in the county of Tama and State of Iowa, have 5 invented certain new and useful Improvements in Vending-Machines, of which the following is a specification.

This invention has relation to mechanism for automatically vending small goods—such as 10 peanuts, candies, and the like—capable of being delivered in loose and measured quantities. In its general organization the vending-machine comprises a delivery-compartment common to two bins or hoppers, said delivery-compartment having its bottom inclined to 15 form a chute and having its front side closed by means of a slide, which normally holds the goods in check and which when moved permits the goods to automatically discharge by 20 gravitational force. The measure, cup, or receptacle for delivering the goods in determinate quantity is slidably mounted and when 25 depressed receives a charge of the goods to be vended and when elevated automatically delivers the same upon an extension of the inclined bottom of the aforementioned delivery-compartment. The measure is held against 30 downward movement by a lock mechanism which must be released preliminary to operation 35 of the machine to effect vendition. The lock mechanism within the purview of the invention may be actuated by any determinate means and for convenience is illustrated for coöperation with a coin of determinate value deposited in a slot and directed by means of a 40 chute or way to proper position for conjoint operation with the lock mechanism to effect a release of the vending mechanism.

For a full description of the invention and 45 the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a vending-machine embodying the invention. Fig. 2 is a vertical central section of the machine. Fig. 3 is a perspective view of the measure, cup, or receptacle. Fig. 4 is a perspective view of the shoe provided at the delivery end of the coin chute or way. Fig. 5 is a horizontal section on the line X X of Fig. 2. Fig. 6 is a horizontal section on the line Y Y of Fig. 2. Fig. 7 is a vertical section on the line Z Z of Fig. 6 of the intermediate portion of the machine, 55 showing the parts on a larger scale. Fig. 8 is a vertical section on the line W W of Fig. 2. Fig. 9 is a detail view of a modified form of coin-chute for ejecting a spurious coin, slug, or analogous device used in an attempt to defraud 60 the machine. Fig. 10 is a top plan view of the coin-chute shown in Fig. 9.

Corresponding and like parts are referred to in the following description and indicated in all the views of the drawings by the same 70 reference characters.

The cabinet or casing for inclosing the working parts is indicated at 1 and may be of any construction or design, according to the caprice of the constructor and the special finish of the machine. Any number of bins or 75 hoppers 2 may be provided at the upper end of the cabinet for receiving the goods to be vended, the bottom of said hopper or bin sloping so as to direct the commodity to a common point of discharge. A measure 3 is mounted to slide vertically through the bottom of the bin or hopper and is directed in 80 its movements by suitable guides. The measure may be of any construction adapted to receive the goods at the top and to discharge the same laterally. A knob 4 or like operating device is connected with the measure 3 by means of a rod or bar 5, which is arranged to operate in a vertical slot 6, formed in the front of the 85 casing. A spring 7 coöperates with the measure to normally hold the same elevated, the upward movement being limited by the rod or bar 5 coming in contact with the upper closed end of the slot 6. The bin or hopper 2 is subdivided by a partition 8, so as to form a 90 space or chamber 9, into which a small proportion only of the goods is received, thereby

95

offering a minimum amount of resistance to the upward movement of the measure or cup, which in its ascent must pass therethrough. The edge of the partition 8 is a short distance 5 above the bottom of the bin or hopper. Hence the goods passing into the chamber 9 beneath the partition 8 practically maintains a uniform level, which is below the plane of the upper end of the measure or cup 3, this being 10 necessary in order to guard against delivery of more goods than the measure or cup will contain at any one time. When the measure descends, its upper end passes below the level 15 of the goods in the chamber 9 and is filled by said goods passing therein. As the measure rises and its upper end passes above the level 20 of the goods in the chamber 9 the side opening 10 of the measure registers with an opening 11 in the inner side of the chamber 9, establishing 25 communication between said chamber and the delivery-compartment, thereby permitting the discharge of the goods from the measure or cup into the delivery-compartment 12 upon the inclined bottom or chute 13 thereof.

The delivery-compartment 12 has a portion located within the casing or cabinet and a portion exterior thereto, the two parts being in communication through an opening 14 in the 30 front wall or side of the cabinet. A cut-off or slide 15 closes the outer side of the delivery-compartment, and in order to admit of inspection of the goods the front plate of the slide or cut-off is of glass. A knob or button 16 is 35 applied to the slide or cut-off for convenience of operation, and when said slide is moved upward the goods contained in said compartment 12 automatically discharge and may be received in the hand or in any convenient and 40 determinate way.

A lock rod or bar 17 is connected with the measure or cup 3 and is movable therewith and is provided with a series of notches 18 for coöperation with one end of a latch 19 to normally hold the measure against downward movement, so as to receive a supply of goods preliminary to effecting vendition thereof. The latch 19 is pivoted near one end to a bracket or support 20 and is pressed upward 45 at its rear end by means of a spring 21, whereby its outer end 22, which normally inclines upward and forward, is held in engagement with the lock-bar, so as to attain the desired end. The rear portion of the latch 19 normally occupies an approximately horizontal 50 position, and its rear end is notched to provide clearance for the hooked or bent end 23 of a rod 24, attached at its lower end to a bar 55 connected to the measure 3, so as to move therewith. The hooked or bent end 23 normally occupies a position above the plane of the notched end of the latch 19 to admit of the coin 26 passing beneath the part 23 and lodging upon the rear notched end of the latch 60 19, as indicated most clearly in Fig. 2. The

measure 3 and lock-bar 17 have sufficient vertical play to admit of depressing the rod 24 a distance to bring its bent end 23 in contact with the coin 26, so as to depress the rear end 65 of the latch 19 and withdraw its front end from engagement with the lock-bar, whereby the measure may move downward to the limit of its travel, so as to receive a supply of goods to be delivered upon the ascent or return of the measure to a normal position. 70

The coin chute or way 27 connects at its upper end with the coin-slot 28 in the front of the cabinet 1 and curves or inclines rearward and downward and connects with a shoe 29, by means of which the coin 26, near the end of its 75 travel, is directed upon the rear end of the latch 19, which extends into the horizontal portion of the shoe. The shoe 29 is approximately of elbow form, and its lower or rear wall is curved and positioned with reference 80 to the chute 27 and latch 19 to direct the coin 26 upon the latter, the forward movement of the coin being arrested by the rod or bar 24, as indicated most clearly in Fig. 2. The horizontal delivery end of the shoe 29 is open at 85 the top and bottom to admit of free movement of the parts 23 and 19.

A vending-machine embodying the essential features substantially as herein set forth and illustrated has the goods to be vended supplied to the hopper or hoppers 2, and said goods pass through the chamber 9 beneath the lower edge of the partition 8. Vendition of a quantity of the goods is effected by depressing the measure 3 to the limit of its downward movement, so as to carry its upper end below the level of the goods received in the chamber 9 when a portion of the goods passes over the sides of the measure into the latter, and upon the ascent of the measure and registry of the openings 10 and 11 the goods automatically pass from the measure into the delivery-compartment 12 and are discharged therefrom by moving the slide or cut-off 15 upward. Preliminary to downward movement of the measure it is first necessary to release the lock mechanism, which is accomplished by depressing the rear end of the latch 19, so as to withdraw its front end from engagement with the lock-bar 17. While this 110 result may be effected in a variety of ways, it is preferred to devise the means illustrated, so that the prospective purchaser may by depositing the prescribed coin into the coin-slot 28 automatically release the lock mechanism 115 simultaneously with depressing the measure or receptacle 3 in the manner hereinbefore stated.

In the modified form of coin-chute shown in Figs. 9 and 10 a delivery-opening 30 is 120 provided in the upper side near the shoe 29, and a spring 31 extends from the coin-chute 28 to the delivery-opening 30, so as to direct a light coin or other article through said opening and prevent operation of the machine by 125 130

a coin other than that determined upon to effect a release of the delivery mechanism.

Having thus described the invention, what is claimed as new is—

- 5 1. In a vending-machine, the combination of a bin having a portion separated therefrom by means of a partition to form a chamber for containing a small proportion of the goods, a measure adapted to operate in the chamber or 10 separated portion of said hopper and open at the top for receiving a supply of the goods and having an opening in the side for automatic delivery, and actuating means for said measure, substantially as set forth.
- 15 2. In a vending-machine, the combination of a bin having a portion separated therefrom by means of a partition to form a chamber for containing a small proportion of the goods, a measure adapted to operate in the chamber or 20 separated portion of said hopper and open at the top for receiving a supply of the goods and having an opening in the side for automatic delivery, a delivery-compartment adapted to receive the goods from the measure, and 25 a cut-off for controlling the discharge of the goods from said delivery-compartment, substantially as specified.
3. In a vending-machine, the combination of a casing, a hopper arranged within the casing and subdivided by a partition to form 30 a chamber for reception of a small proportion of the goods to be vended, a measure mounted for reciprocal movement within the

said chamber and adapted to receive the goods at its upper end and to discharge the same laterally, a delivery-compartment having a portion located within the said casing and a portion exterior thereto and adapted to receive the goods from said measure, and a cut-off for closing the discharge of said delivery-compartment, substantially as set forth. 35

4. In combination, a casing, a hopper within the casing and subdivided by a partition to form a chamber adapted to receive a small proportion of the goods to be vended, a measure mounted for vertical movement within said chamber and having its upper end and one side open, a delivery-compartment having a portion located within said casing and a portion exterior thereto, the parts of the delivery-compartment being in communication through an opening in a side of the casing, the inner portion of said delivery-compartment being in communication with the chamber or partition portion of the aforementioned hopper so as to receive the goods from the measure, and a cut-off for closing the discharge-opening of the delivery-compartment, substantially as specified. 40 45 50 55

In testimony whereof I affix my signature in presence of two witnesses. 60
